UNITED STATES PATENT OFFICE.

THEOBALD F. UNGEMACH, OF ZANESVILLE, OHIO.

SEWING-MACHINE SHUTTLE.

SPECIFICATION forming part of Letters Patent No. 271,552, dated January 30, 1883.

Application filed November 20, 1882. (No model.)

To all whom it may concern:

Be it known that I, THEOBALD F. UNGEMACH, a citizen of the United States, residing at Zanesville, in the county of Muskingum and State of Ohio, have invented a new and useful Sewing-Machine Shuttle, of which the following is a specification, reference being had to the accompanying drawings.

This invention relates to sewing-machine shuttles; and it consists in certain improvements in the construction of the same, which will be hereinafter fully described, and particularly pointed out in the claim.

In the drawings hereto annexed, Figure 1 is a perspective view of my improved sewing-machine shuttle. Fig. 2 is a longitudinal vertical section of the same, and Fig. 3 is a detail view of the tension-spring and adjusting-screw detached.

20 The same letters refer to the same parts in all the figures.

The object of my invention is to provide sewing-machine shuttles with a simple and convenient tension device, by means of which the movement of the bobbin may be retarded without passing the thread through a series of friction-openings, as is now commonly done, whereby the thread is invariably more or less worn and damaged. This I accomplish by the 25 construction and arrangement of parts which I shall now proceed more fully to describe with reference to the drawings, in which—

A represents the body of my improved shuttle, which is mainly of the ordinary construction, and provided with the recess B to receive the bobbin C. On one side of the slot or recess B the shuttle is provided with a slot, D, across which is secured a guide-bar, E. On the other side of the recess is an opening or

eye, F, forming a thread-guide. The heel of 40 the shuttle is provided with a longitudinal screw-threaded opening, G, to receive a screw, H, provided in its inner end with a recess, I, in which is fitted a spring, J, carrying at its outer end a plate, K, forming a bearing for 45 one end of the bobbin. A bearing for the other end of the bobbin is formed at the front end of the recess B.

The operation and advantages of my invention will be readily understood from the foregoing description, taken in connection with the drawings hereto annexed.

By manipulating the screw the pressure of the spring may be regulated, so as to retard the motion of the bobbin to any desired extent.

For sewing in light fabric the thread may be threaded through the slot D, over the guide-bar E, and through the eye F. For heavy goods it will be found sufficient to pass it 60 through the eye F.

I claim as my invention and desire to secure by Letters Patent of the United States—

As an improvement in sewing-machine shuttles, the body A, having recess B, slot D, 65 guide-bar E, and eye F, and provided in its heel with a longitudinal screw-threaded opening, G, in combination with the screw H, having recess I, spring J, and bearing-plate K, as and for the purpose set forth.

In testimony that I claim the foregoing as my own I have hereto affixed my signature in presence of two witnesses.

THEOBALD FREDRICK UNGEMACH.
